BUILDING BLOCK FOR WALLS, COLUMNS AND THE LIKE

Norman Kenneth Carlberg, New Haven, Conn.

Application February 7, 1958, Serial No. 49,544

Term of patent 7 years

(Cl. D18—2)

The figure is a perspective view of a building block for walls, columns and the like, showing my new design. The other sides of the article not shown are substantially like the side shown.

I claim:

The ornamental design for a building block for walls, columns and the like, as shown and described.
